US0D1058139S

(12) **United States Design Patent** (10) Patent No.: **US D1,058,139 S**
 Dente (45) Date of Patent: ** Jan. 21, 2025

(54) HEEL TRACTION DEVICE	1,032,600 A *	7/1912	Grout	A43C 15/063
(71) Applicant: Dentec Safety Specialists Inc. , Newmarket (CA)	1,117,019 A	11/1914	Foltz	36/62
	1,195,866 A	8/1916	Stephan	
	1,275,917 A	8/1918	Herman	
(72) Inventor: Claudio Dente , Newmarket (CA)	1,386,028 A	8/1921	Roe	
	1,437,376 A	11/1922	Young	
	1,458,497 A	6/1923	Perkins	
(73) Assignee: Dentec Safety Specialists Inc. , Newmarket (CA)	1,493,322 A	5/1924	Carter et al.	
	1,552,946 A	9/1925	Frederick	
	1,564,307 A	12/1925	Antonio et al.	
(**) Term: 15 Years	1,596,832 A	8/1926	Heinemann	
(21) Appl. No.: 29/823,646	1,757,919 A	5/1930	Ostrander	
(22) Filed: Jan. 19, 2022	1,869,988 A	8/1932	Stephen	
(30) Foreign Application Priority Data	2,128,134 A	8/1938	Nicola	
Jul. 23, 2021 (CA)	2,166,958 A	7/1939	Lawson

CLAIM

The ornamental design for a heel traction device, as shown and described.

DESCRIPTION

FIG. 1 is a top perspective view of a heel traction device, according to a new design;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The broken lines in the drawings depict portions of the heel traction device that form no part of the claimed design.
